UNITED STATES PATENT OFFICE.

THOMAS J. McDONALD AND WILLIS R. WOOLRICH, OF KNOXVILLE, TENNESSEE; SAID
WOOLRICH ASSIGNOR TO THE SAID McDONALD.

PORTABLE WASHING MACHINE.

Application filed May 2, 1925. Serial No. 27,526.

This invention relates to washing machines, and more particularly to improvements in a portable machine, the parts of which are so arranged that the clothes may be effectively washed, rinsed and dried without removing the clothes from the receptacle during the various processes.

A primary object of the invention is to provide a portable washing machine with means whereby a revoluble tub is arranged to rotate around a horizontal axis during the washing operation to thoroughly clean the clothes, and is driven about a vertical axis during the rinsing and drying operation to dry the clothes before they are removed from the tub.

A further object of the invention consists in operatively connecting the rotatable tub to a motor in such a manner that the rotation of the tub may be varied so as to revolve faster during the rinsing and drying operation than when the clothes are being washed.

The invention further comprehends the provision of means for preventing the clothes from balling up and becoming entangled during the operation of the machine.

Referring to the drawings, wherein is set forth a preferred embodiment of the invention:

Figure 1 is a plan view of the machine, Figure 2 is a side elevational view of the invention, showing in dotted lines, the machine in horizontal position.

Figure 3 is an enlarged vertical sectional view of Figure 2,

Figure 4 is a view taken substantially along the lines 4-4 of Figure 3,

Figure 5 is a detailed view showing the adjusting means for securing the container in vertical position, and

Figure 6 is a detailed view of the operating handle and its associated parts.

Referring to the drawings, in which like numerals indicate like parts in the several views, 10 denotes a metallic supporting frame which, preferably, comprises tubular side bars 11 connected together by the cross bars 12. The bars 11 slope inwardly at their upper ends and are provided with the retaining lugs or bearings 14 arranged to receive the trunnions 15 carried by a central band 16 which encircles the metal container or receptacle 17. The container 17 is additionally surrounded at its upper end

by a band 18, to which is connected wing nuts 19, preferably four in number, and suitably spaced apart. A reinforcing cup or band 20 encircles the lower portion of the container and has attached thereto a pair of yieldable clamps 21, each of which is provided with a vertical slot 22 arranged to receive a threaded bolt 23 that extends from the cups 20 and to which is connected a wing nut 24 so as to permit the clamps 21 to be adjusted vertically relative to the cup 20. Furthermore, the lower portion of the clamp 21 is preferably curved so as to be of the same contour as the transverse bars 12, to which they are detachably connected. The container 17 adjacent the ring 18 has suitably secured thereto diametrically opposed handles 25 for permitting the container to be conveniently placed on or removed from the supporting frame 10.

A revolving tub 26, preferably of hexagonal formation in cross section, is mounted within the container 17, and is provided with the perforations 26' and a series of vertical corrugations 27 on its inner walls so as to cause an effective cleaning of the clothes carried by the tub during the washing operation. The inner wall of the tub 26 is further provided with opposed inwardly extending protuberances or thimbles 28 struck out from opposite sides of the tub, and preferably positioned in a line to form an oblique angle to the vertical to prevent the clothes from balling up or becoming entangled during the washing operation. The tub 26 is rotatably mounted within the container 17 by means of a spindle 29, which projects upwardly and centrally from the bottom of the container 17 and fits within a complementary recess 30 formed in the bottom of the tub 26. The top of the tub 26 is closed by a lid 31 which frictionally engages the inner wall thereof. The outer face of the lid 31 has a central boss 33 provided with a recess 34 preferably of square or polygonal shape so as to receive a correspondingly formed member carried by the drive shaft hereinafter referred to.

A motor supporting frame 35 has extending from the lower portion thereof laterally forked flanges 36 arranged to receive the wing nuts 19 so as to detachably, but firmly, secure the support 35 and the lid 31 to the container 17. A motor 37 of any suitable horsepower is mounted upon the support 35.

and is operatively connected to the main drive shaft 38 through the instrumentality of a variable gear mechanism which comprises a shaft 39 having a bevel gear 40 in mesh with a complementary gear 41 on the vertical shaft 42. The shaft 42 has its upper end extending through a housing 43 while its lower portion is supported by the spaced webs 44 and 45 formed in the frame 5. A slideable sleeve 46 is mounted on the shaft 42, and extends through a bushing 47 carried by the web 44. The lower portion of the sleeve 46 has a gear 48 arranged to mesh with a large gear 49 keyed to the main shaft 10. Below the gear 48, the sleeve 46 is provided with a smooth surface 50, arranged to frictionally engage a complementary surface 51 formed in the clutch 52. The clutch 52 is supported by the thrust bearings 53 carried in a recess formed in the lower web 20 45 of the support, and is provided exteriorly with a series of gear teeth 54 in mesh with a small gear 55, keyed to the main shaft 38 below the large gear wheel 25 49. The motor 37 is adapted to be selectively connected to either the gear 49 or the gear 55 by means of a shifting lever 56 which has its inner end confined between the flanges 57 on the sleeve 46, while its opposite 30 35 extremity is secured to a vertical rack 59, movable in suitable guides formed in a cover plate 66. The rack 59 meshes with a pinion 60 carried by the operating handle 61. A yieldable plunger 61' extends laterally from the handle 61 and is adapted to engage the notches 67 in the plate 66 so as to maintain the handle 61 and its associated parts in fixed position. It will be seen that by reason of this construction the handle 61 may 40 45 be operated to bring the gear 48 in mesh with the large gear 49 for rotating the tub during the washing operation, or may move the sleeve 46 downward so as to cause the surface 50 to frictionally engage the complementary surface in the clutch 54, so as to drive the gear 55 and cause the tub to rotate at a relatively much faster speed than when driven through the gear 49.

50 55 A pulley 63, carried by the shaft 39, and a pulley 62, mounted on the auxiliary shaft 42 permits the motor to be used for other driving purposes when the same is desired. In order to prevent the lubricating oil from dripping into the tub, a cup 58 is secured to the underside of the transverse web 45.

The operation of the device is as follows: Assuming the clothes to be washed to be in the tub 26, and the container 17 supplied with the necessary amount of water 60 65 and journalled to the supporting frame 11 by engagement of the trunnions 15 with the bearings 14, the clothes will be subjected to the washing treatment by swinging the container 17, the tub 26, and the motor 37 to the horizontal position as indicated in dotted lines in Figure 2, in which position the lower clamp 21 will engage the adjacent cross bar 12 so as to prevent movement of the container relative to the frame 10. The operating handle 61 at the same time, is moved to the position as shown in Figure 2, so as to bring the gear 48 in mesh with the gear 49 of the main drive shaft 38, and thus cause the tub 26 to revolve about its horizontal axis. During this operation, the clothes are prevented from balling up by reason of the particular position of the cups 28, which, it will be observed, are staggered so as to lift the clothes to the top of the tub and then allow them to drop to the bottom. After the clothes have been thoroughly washed, the water is removed both from the container 17 and the tub 26 through a drain pipe 64, positioned in the bottom of the container 17. The container 17, together with the tub 26 and motor 37, are then swung to the vertical position as shown in full lines in Figure 2, and the operating handle 61 is actuated so as to cause the surface 50 of the sleeve 46 to frictionally engage the interior of the clutch 54, which directly connects the motor with the small gear 55 of the main shaft 38, and causes the tub 26 to revolve at a much higher rate of speed than that at which it was driven during the washing operation. Due to the high centrifugal force at which the clothes are driven during the wringing operation, they will be effectively dried in a very short period of time, and then can be easily removed from the container by detaching the lid 31 from the tub 26.

This machine is particularly adapted for use in apartment houses and places where space is very limited. In addition to the device being arranged to be supported directly on the ground, it may be fixedly mounted within a bath tub or the like by means of the threaded screws 65 which extend laterally through the arms 11, and are adapted to frictionally engage the adjacent sides of a bath tub. It will be observed that the parts are all detachably, but firmly, connected to each other so that the machine may be readily dismantled or set up at a minimum expenditure of time and labor.

It is to be understood that the form of the invention herewith shown and described is merely illustrative, and in no sense restrictive, and that such changes as fall within the purview of one skilled in the art may be made without departing from the spirit of the invention and the scope of the appended claims.

We claim:

1. A washing machine of the class described comprising a stationary support, a container pivotally mounted on said support and having an open top, a revolving perforated tub journalled in the bottom of said

5 container, a cover detachably connected to said top, a motor mounted on the cover, means connecting the motor to the top of the tub for the driving the same, and means for detachably connecting the container to the support in either of two positions.

2. A washing machine of the class described comprising a stationary support including transverse end bars, a container 10 pivotally mounted on said support and having an open top, said container adapted to be swung either to a horizontal or vertical position relative to the support, a revolving perforated tub journalled in the bottom of 15 said container, a cover detachably connected to said top, a motor mounted on the cover, means connecting the motor to the top of the tub for driving the same, and yieldable means on the container adapted to engage 20 the transverse bars for maintaining the container and motor in either a horizontal or vertical position.

3. A washing machine of the class de-

scribed comprising a stationary support including transverse end bars, a container 25 pivotally mounted on said support and having an open top, said container adapted to be swung either to a horizontal or vertical position relative to the support, a revolving perforated tub journalled in the bottom of 30 said container, thimbles projecting inwardly from said tub and positioned in a line to form an oblique angle to the vertical, a cover detachably connected to said top, a motor mounted on the cover, means connecting the 35 motor to the top of the tub for driving the same, and yieldable means on the container adapted to engage the transverse bars for maintaining the container and motor in either a horizontal or vertical position. 40

In testimony whereof I have hereunto set my hand this 1st day of May, 1925.

THOMAS J. McDONALD.

In testimony whereof I have hereunto set my hand this 27th day of April, 1925.

WILLIS R. WOOLRICH.
